UNITED STATES PATENT OFFICE.

DE ROY AUSTIN, OF OMAHA, NEBRASKA.

SHOE.

1,078,571.

Specification of Letters Patent. Patented Nov. 11, 1913.

Application filed January 16, 1912. Serial No. 671,530.

To all whom it may concern:

Be it known that I, DE ROY AUSTIN, a citizen of the United States, and a resident of Omaha, in the county of Douglas, and 5 State of Nebraska, have invented certain new and useful Improvements in Shoes, of which the following is a specification.

My invention relates to the manufacture of boots and shoes, and more particularly 10 to the construction of shoes having resilient or cushion insoles.

It is the object of my invention to provide in a shoe a resilient or cushioning insole disposed adjoining the foot and securely 15 held in place without the use of paste, cement or special seams to secure it to the leather insole, and in which the transverse strength of the cushioning material is made use of to increase the stability of the shoe. 20 A further object of my invention is to provide in a shoe an efficient means for protecting the heel of the wearer from the protruding ends of tap-nails.

In the accompanying drawings Figure 1 25 is a side view, partially in vertical longitudinal section, of a shoe embodying my invention, Fig. 2 is a transverse vertical section of the same, Fig. 3 is a similar view showing a slight modification of the structure, Fig. 4 is a perspective view showing the bottom of the composite insole, and Fig. 5 is a detail transverse section showing another slight modification of the structure.

In carrying out my invention I employ 35 an upper 1, an outsole 2, and a welt 3, all of ordinary construction and arrangement. The insole, however, is a composite structure and comprises a sheet 4 of leather corresponding to the usual leather insole, a sheet 40 5 of fibrous resilient material such as felt disposed over the leather sheet, and a lining-piece 6 of soft material such as kid leather disposed over the felt sheet. The edges of the toe and shank portions of the felt sheet 45 are split so as to form two lips 7 and 8. The lower lip 7 is turned down around the outer edges of the leather insole and when the inseam 9 is made it is passed through the marginal part of the leather insole in the usual way and also passes through the down-turned lip 7 of the felt insole so that said lip 50 is secured between the edge of the leather insole and the upper.

The lining-piece 6 may be made coincident with the upper surface of the felt sheet and secured thereto by a marginal seam

10 passing through the lip 8, as shown in Figs. 1, 2 and 4, or the lining-piece may be made large enough to enable the edge portion thereof to be turned down and pass entirely around the lip 8 and adjoin the outer side of the lip 7 so as to be secured by the inseam 9 between the lip 7 and the upper, as shown in Figs. 3 and 5. When the edges of the lining-piece are thus secured by the inseam the marginal seam 10 may be omitted as shown in Fig. 3, or a similar seam 11 may be passed through the two thicknesses of the lining-piece and the lip 8, as shown in Fig. 5.

In the completion of the heel portion of the shoe it is preferable that the tap-nails 12 be not driven through the felt portion of the insole but shall terminate at the upper surface of the lower or leather part of the 75 insole. In driving the said nails the heel portion of the felt sheet may be turned up as shown by dotted lines in Fig. 1, and then turned down to the normal position shown to cover the ends of the nails and protect 80 the heel of the wearer from them.

It will be obvious that by the construction shown the resilient sheet 5 is securely held in position in the shoe; that the transverse strength of the said sheet 5 is added to that 85 of the leather part of the insole to increase the stability of the shoe, so that equal strength may be obtained with a lighter and less expensive leather insole than is usually employed; that the resilient sheet need not 90 be secured in position by paste or cement and, being held in position entirely by means of the regular inseam, no special seaming operation is necessary in securing it in position; and that the lip 8, by extending out 95 over the inseam, forms a cushion for the extreme edges of the foot.

Now, having described my invention, what I claim and desire to secure by Letters Patent is:

1. In a shoe having an upper, a welt, a leather insole and an inseam for securing them together, a sheet of fibrous resilient material disposed above the leather insole and having a lip extending between the 105 upper and the margin of the leather insole, the inseam passing through said lip.

2. In a shoe, a composite insole comprising a sheet of leather, a sheet of fibrous resilient material disposed over the leather 110 sheet and having a marginal lip inclosing the edges of the leather sheet, and a lining

2
secured over the top of the fibrous resilient sheet, an upper, a welt, and an inseam passing through and securing together the upper, the welt and all parts of the composite in-

5 sole.
3. In a shoe, an upper, a welt, an insole, and an inseam passing through and securing them together, the insole comprising a sheet of leather, a sheet of felt disposed over the same and having the edges of the toe and shank portions thereof split to form two lips, the lower lip being turned down around the edges of the leather sheet and being traversed by the inseam, and a lining-
10 piece disposed over the felt sheet and having its marginal portion secured to the upper lip thereof.

15 4. In a shoe, an upper, a leather insole, a felt insole disposed over the leather insole and having marginal portions extending
20

down around the edges of the leather insole, a covering secured over the felt insole, and a seam passing through the adjoining portions of the felt insole, the leather insole and the upper to secure them together.

25

5. In a shoe, an upper, a welt, a leather insole, a felt insole secured over the leather insole, an inseam passing through and securing together the welt, the upper, and the toe and shank portions of the leather and 30 felt insoles, and tap-nails extending through the leather insole only and having their inner ends covered by the felt insole.

30

In testimony whereof I have hereunto subscribed my name in the presence of two witnesses.

35

DE ROY AUSTIN.
